CLUSTER-TYPE PUSHBUTTON SWITCH

James R. Cochrane, Chicago, Ill., assignor to General Electric Company, a corporation of New York

Filed Dec. 14, 1964, Ser. No. 83,023

Term of patent 14 years

(Cl. D26—13)

FIG. 1

FIG. 2

72504

FIG. 3

FIGURE 1 is a front elevational view of the cluster-type pushbutton switch of my invention;

FIGURE 2 is a top plan view thereof; and

FIGURE 3 is a side elevational view of the left side thereof as shown in FIGURE 1.

The bottom of the cluster-type pushbutton switch is substantially the same as the top thereof shown in FIGURE 2, and the right side thereof is substantially the same as the left side thereof shown in FIGURE 3.

The dominant features of my new design reside in the portions shown in full lines.

I claim:

The ornamental design for a cluster-type pushbutton switch, substantially as shown and described.
